UNITED STATES PATENT OFFICE.

CLARENCE A. FULLERTON, OF NEW YORK, N. Y.

DESIGN FOR A DISPLAY SIGN.

Application filed March 27, 1925. Serial No. 12,914. Term of patent 7 years.

To all whom it may concern:

Be it known that I, CLARENCE A. FULLERTON, a citizen of the United States of America, residing in the borough of Manhattan, city, county, and State of New York, have invented a new, original, and ornamental Design for Display Signs, of which the following is a specification, reference be-

ing had to the accompanying drawing, forming a part thereof.

The drawing is a perspective view of a display sign showing my new design.

I claim:

The ornamental design for a display sign, substantially as shown.

CLARENCE A. FULLERTON.
